Primary Examiner — Freda S Nunn(74) *Attorney, Agent, or Firm* — Lerner, David, Littenberg, Krumholz & Mentlik, LLP(57) **CLAIM**

The ornamental design for a notebook computer housing, as shown and described.

DESCRIPTION

FIG. 1 is a perspective view of a notebook computer housing according to our design;

FIG. 2 is a top view thereof;

FIG. 3 is a bottom view thereof;

FIG. 4 is a front side view thereof;

FIG. 5 is a back side view thereof;

FIG. 6 is a right side view thereof; and,

FIG. 7 is a left side view thereof.

The broken lines shown in FIGS. 1, 2 and 4 that are immediately adjacent to the shaded areas represent the bounds of the claimed design, while all other lines are directed to environment and form no part of the claimed design.

1 Claim, 7 Drawing Sheets(56)
